Primary Examiner—James R. Largen
Attorney, Agent, or Firm—Quarles & Brady

[57] CLAIM

The ornamental design for a bidet, as shown and described.

DESCRIPTION

FIG. 1 is a perspective view taken from the top, front and left side of a bidet embodying our new design;
 FIG. 2 is a top plan view thereof;
 FIG. 3 is a left side elevational view thereof, the right side being the mirror image of the left side; and,
 FIG. 4 is a front elevational view thereof.
 The fragmentary broken line representations of holes in FIGS. 1 and 2 are for the purpose of illustration only and form no part of the claimed design.

FIG. 1

FIG. 4
